JACK

Herbert E. Page, Pasadena, Calif.

Application March 6, 1944, Serial No. 525,260

13 Claims. (Cl. 254—93)

1

This invention has to do with lifting devices such as jacks and has for one of its objects the provision of a jack embodying, in combination with hydraulic lifting means, mechanical means for releasably engaging the lifting piston to relatively quickly move said piston into initial contact with the work to be lifted.

It is a further object of the invention to provide, in such a jack, resilient means for disengaging the mechanical lifting means from the work-lifting piston.

Another object is to provide in such a jack a novel collar for releasably engaging and moving the piston into initial contact with the work to be lifted.

Still further advantages are provided by my invention and will become apparent from the following detailed description of preferred embodiments which I have chosen for the purpose of explanation. I wish it understood, however, that I do not intend to confine the invention to the precise details of structure and association of parts now to be set forth because the invention is susceptible of being carried out in other physical embodiments which the following explanation will suggest to those working in the art.

In connection with the following description I shall refer to the accompanying drawings, in which:

Fig. 1 is a cross section taken on line 1—1 of Fig. 2;

Fig. 2 is a vertical section taken on line 2—2 of Fig. 1;

Fig. 3 is a front view with the front wall removed, being shown partly in section;

Fig. 4 is a top plan view of a modified form of my invention;

Fig. 5 is an enlarged medial vertical section of the jack of Fig. 4, some parts being shown in elevation;

Fig. 6 is an enlarged front elevation of the jack of Figs. 4 and 5;

Fig. 7 is an enlarged fragmentary section showing a modified form of lifting collar; and

Fig. 8 is an enlarged fragmentary section showing a modified form of connecting rod.

Referring first to Figs. 1, 2 and 3, I show a body comprising a base 5, side walls 6, and cover 7; the side wall being of oval cross section and secured to the cover and base by means of screws 8, although, of course, the body may be formed in other manners well-known in the art.

A cylinder 10 has its bottom, exteriorly threaded end 10a threadedly mounted in a corresponding recess in the base 5 and a cylinder

2

12 providing a fluid reservoir R is mounted in the body, the cylinder 12 having its threaded reduced lower end 12a threaded into a recess 15 in the base, and presenting a port 16. A threaded plug 17 closes the top end of cylinder 12, the plug having a port 18 to atmosphere.

A piston 30 having an interiorly threaded upper end portion 30a is reciprocally disposed in cylinder 10, there being a core 31 threadedly mounted in the portion 30a for extension purposes. The top end of core 31 provides a work-contacting pad 32, the piston being protractable and retractable through an opening 35 in cover 7. A guide ring 37 is provided between the cylinder interior and piston portion 30a and a seal ring 38 is provided in an annular recess in piston 30.

A second cylinder 40 is provided in the base, said cylinder being of relatively smaller diameter than cylinder 10 and having mounted therein a piston 45 whose lower end forms with the cylinder a pressure-generating chamber 46. Piston 30 forms with cylinder 10 a main pressure chamber 47.

Chamber 46 communicates with the reservoir through ports 50, 51, 52 formed in the base and port 16 formed in the neck 12a of the reservoir cylinder, said communication being controlled by a ball check valve 55 which is normally maintained seated towards the reservoir by a coil spring 56 disposed around a slide bar 57. Thus on the up or suction stroke of piston 45 in chamber 46, the vacuum created in that chamber will draw fluid from the reservoir past valve 55.

Chamber 46 communicates with chamber 47 on the down or pressure stroke of piston 45 through a port 60 when the pressure in chamber 46 is sufficient to overcome the pressure of a spring 62 which normally urges a ball check valve 61 seated towards chamber 46.

An operating shaft 65 is journaled in a bifurcated boss 68 carried by the base, being oscillated by a lever 66. Oppositely disposed arms 69, 70 are secured, as by splining, on the shaft 65 arm 69 being pivotally connected to the bifurcated top end of piston 45 by a link 71 and cross pins 72.

A collar 75 having a diagonal bore 76 somewhat loosely fits over piston 30a, said collar being urged into a position of rest horizontally against the top end of cylinder 10 by springs 77, 78, in which position the collar is normal to the piston portion 30a. Spring 77 is secured at its top end to a peripheral flange 77a of collar 75 by means of link 77b, and is secured to the base at its opposite

end. The top end of spring 78 is secured to an opposite peripheral flange 78a of the collar by a link 79 whose lower end is cone-shaped and fits in the similarly shaped top end of spring 78. The lower end of spring 78 is secured to arm 70 by a similar link 80.

Operation of the device of Figs. 1, 2 and 3 is as follows: To establish initial contact of the pad 32 with the work to be lifted, the lever 66 is lifted, which draws fluid from the reservoir into chamber 46. Upon downward movement of the lever, arm 70, through the medium of the spring 78, will raise the left-hand side of collar 75, causing the collar to bind on the piston portion 30a and mechanically lift that piston upward, and piston 45 will force the fluid from chamber 46 into chamber 47 past the valve 61. If one such oscillation of shaft 65 is insufficient to contact the pad 32 with the work, the operation may be repeated until such contact is established. As piston 30 is thus mechanically pulled from cylinder 10 the small amount of fluid forced from chamber 46 will be insufficient to supply adequate make-up fluid to chamber 47. Thus additional make-up fluid will be drawn from the reservoir through a passageway 82 and past ball valve 83, which latter valve seats towards the reservoir.

It will be understood that during each upward movement of lever 66 the left-hand side of collar 75 will be pulled downwardly by spring 78 and the right-hand side of the collar will be pulled downwardly by spring 77. The diagonal bore through collar 75 insures against the collar binding on the piston portion 30a during any unevenness in such downward movement.

After the pad 32 is thus contacted with the work to be lifted, further oscillation of shaft 65 by lever 66 will cause fluid to be drawn from the reservoir into chamber 46 on each suction stroke of piston 45 and each pressure stroke will force fluid past valve 61 into chamber 47 and thus piston 30 will be gradually elevated hydraulically by pressure transmitted to chamber 47. During this latter lifting operation, of course collar 75 will continue to be moved up along with the piston portion 30a and downward relative thereto on each suction stroke of piston 45, but no effective lifting force on piston portion 30a will be exerted in this manner. Inasmuch as the fluid pressure increase in chamber 47 on each pressure stroke of piston 45 will be insufficient to raise piston 30 a distance equal to the distance of travel of the left-hand end of arm 70, I so construct spring 78 that, in its normal position of rest, it is not fully compressed so that arm 70 will be permitted to complete its full upward movement by a slight compression of spring 78 from its normal position of rest.

To lower the load being lifted by the jack, I provide a valve-actuating member 85 which has a portion 85a threadedly mounted in a bore 86 in the base, and a rod portion 85b which is adapted to contact and push ball 55 off its seat to release pressure in chamber 46 and the rod 57 is contacted by ball 55 to move ball 61 off its seat to release pressure in chamber 47, thus allowing the fluid in both chambers to return to the reservoir. After the jack is fully lowered, the valve-actuating member 85 is mechanically rotated in the reverse direction to allow valves 55 and 61 to be returned to their seats by their respective springs, so that the jack is ready for another lifting operation.

In the modified form of Figs. 4, 5 and 6 I show

a body consisting of a base 90, side wall member 91 and cover 92.

The cylinder 10, reservoir cylinder 12, piston 30, piston portion 30a and jack pad 32 are constructed and mounted as before described and are therefore given like reference numerals. Likewise, passageways 50, 51, 52, 60 and 82 and the valve elements controlling those passageways are the same as before described and are given like reference numerals.

Here a piston 100 reciprocates in chamber 46 and has an oppositely disposed guide stem 101 reciprocally disposed in a cylindrical portion 102 of the cover, the upper end of guide portion 101 being exposed to atmosphere through a port 104. Fulfcrumed in the enlarged medial portion 103 of the piston member, I provide an operating lever 105 having a handle 106, the lever being fulcrumed by a cross pin 107. The lever extends outwardly through an opening 108 in the front of the body side wall, which opening is protected against entry of dust, etc., by a flexible rubber covering 110.

The inner bifurcated end 105a of the lever is pivotally connected to a rod 115, the top end of which rod is pivotally connected by cross pin 116 to bifurcations 125 projecting outwardly from the periphery of the collar 120. Collar 120 has a diagonal bore 120a, such as before described, to prevent binding upon its downward movement. A leaf spring 126 is secured to rod 115 by screws 127 and bears against the top surface of collar 120 to urge the collar towards the top end of the cylinder 10.

35 A coil spring 130 has its top end connected to the lower end of rod 115 and has its bottom end secured to the base so that it normally pulls downwardly on the rod 115 and on the lever arm 105a.

40 In operation, to establish initial contact of the pad 32 with the work, operation of the lever fulcrumed about pin 107 will, on each downward movement of the lever, cause collar 120 to grab and raise piston portion 30a. Here, however, 45 instead of fluid being forced from fluid chamber 46 into chamber 47 on each downward stroke of the lever during the operation of establishing initial contact of the pad with the work, as before described, the fluid is trapped in chamber 46 since here spring 62 is of a strength which will not yield until there is such resistance to upward movement of the jack pad 32 as will be afforded by contact with the load. Thus on each successive operation of the lever 105, while such 50 contact is being established, the fulcrum point 107 will be raised since, on each upward movement of the lever, piston 100 will be further withdrawn from chamber 46 and additional fluid will be drawn into that chamber from the reservoir and trapped until pad 32 contacts the load. Thereafter, upon each pressure stroke of piston 100, sufficient pressure will be generated in chamber 46 to unseat valve 61 against spring 62, causing fluid to be forced under pressure into chamber 47.

55 Make-up valve 83 and passageway 82 will allow fluid to flow in chamber 47 during the initial movement of piston 30 before the load is contacted.

60 In Fig. 7 I show a modified form of lifting collar 150 which differs from those before described only in that it is comprised of spaced resilient leaves 150a formed integral with peripheral flange 150b, which provide a more posi-

tive grabbing action on the piston to lift the latter into initial contact with the work load.

In Fig. 8 I show a modified form of rod 160 for connecting arm 105a (Fig. 5) with collar 120, which rod provides means for rendering the jack inoperative when subjected to an overload. Here the rod consists of a cylindrical upper portion 161 longitudinally slotted at 162. The upper end portion of the rod, not shown, is like that of rod 115, for connection to the collar. The lower portion 165 of the rod forms a plunger reciprocable in the base of portion 161, having radial pins 166 projecting into and movable along slots 162. A compression spring 167 is interposed between shoulder 165a of portion 165 and shoulder 161a of portion 161, being disposed spirally around the rod. The spring 167 is made of a strength which will cause it to yield to a predetermined compressive pressure, which would accord with the maximum load capacity of the jack. Thus, since when hydraulic pressure is being generated by piston 100 to create lifting pressure in chamber 41, the fulcrum for lever 106 is on the pivotal connection 168 of rod 160 to arm 105a, spring 167 will yield when downward pressure is applied to lever 106 if the jack is overloaded, with the result that arm 105a will swing upwardly instead of providing a fulcrum.

I claim:

1. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber, check valve controlled means providing communication between the pressure-generating chamber and the main pressure chamber, and means for mechanically moving the work piston into initial contact with the work to be lifted, comprising a link carried by the lever and in continuous operative engagement with the work piston.

2. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber, check valve controlled means providing communication between the pressure-generating chamber and the main pressure chamber, and means for mechanically moving the work piston into initial contact with the work to be lifted comprising a collar loosely fitting around the work piston, and a link operatively connected to the lever and engaging a peripheral portion of the collar.

3. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber,

check valve controlled means providing communication between the pressure-generating chamber and the main pressure chamber, and means for mechanically moving the work piston into initial contact with the work to be lifted comprising a collar normally disposed normal to the work piston and having a diagonal bore through which the work piston extends, and a link operatively connected to the lever and engaging a peripheral portion of the collar.

4. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber, check valve controlled means providing communication between the pressure-generating chamber and the main pressure chamber, and means for mechanically moving the work piston into initial contact with the work to be lifted comprising a collar loosely fitting around the work piston, and a resilient link operatively connected to the lever and engaging a peripheral portion of the collar.

5. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber, check valve controlled means providing communication between the pressure-generating chamber and the main pressure chamber, and means for mechanically moving the work piston into initial contact with the work to be lifted comprising a collar loosely fitting around the work piston and a coil spring secured at one end to the lever and secured at its other end to a peripheral portion of the collar.

6. In a jack, the combination of a body presenting a fluid reservoir, a main pressure chamber and a pressure-generating chamber, a work piston reciprocally mounted in the main pressure chamber, a pumping piston reciprocally mounted in the pressure-generating chamber, a lever fulcrumed on the body and operatively connected to the pumping piston, check valve controlled means providing communication between the reservoir and the pressure-generating chamber, check valve controlled means providing communication between the pressure-generating chamber and the main pressure chamber, and means for mechanically moving the work piston into initial contact with the work to be lifted comprising a collar loosely fitting around the work piston, a link operatively connected at one end to the lever and connected at its other end to a peripheral portion of the collar, and spring means bearing against a diametrically opposite portion of the collar.

7. In a jack the combination of a body presenting a pressure chamber, a pressure generating cylinder and a fluid reservoir, a ram reciprocally mounted in the chamber, valve controlled ports interconnecting the pressure chamber, the pressure generating cylinder and the reservoir,

a pumping piston reciprocally mounted in the pressure generating cylinder for hydraulically raising the ram, a collar loosely engaging the ram, an actuating rod connected at one end to the peripheral portion of the collar, and an operating lever pivotally connected at longitudinally spaced points to the pumping piston and to the other end of the rod whereby upon movement of the lever in one direction it fulcrums on the piston and axially moves the rod and whereby upon movement of the lever in the other direction it fulcrums on the rod and axially moves the pumping piston.

8. In a jack, the combination of a body, a work-lifting piston reciprocally mounted in the body, a lever fulcrumed on the body, a collar loosely fitting around the piston, and means operatively connecting the lever to a peripheral portion of the collar, said collar being comprised of spaced flexible laminae disposed one above another.

9. In a jack, the combination of a body presenting a pressure chamber and a pressure-generating chamber, a work piston reciprocally mounted in the work chamber, a pumping piston reciprocally mounted in the pressure-generating chamber, a collar loosely fitting around the work piston, a shaft disposed transversely of and journaled in the body, means for oscillating said shaft, a pair of oppositely disposed arms secured on the shaft, one of said arms being operatively secured to the pumping piston, means resiliently connecting the other arm to the collar including a coil spring secured at one end to said arm and secured at its other end to a peripheral portion of the collar, and spring means bearing against another portion of the collar to normally urge it into position normal to the work piston.

10. In a jack, the combination of a body presenting a pressure chamber and a pressure-generating chamber, a work piston reciprocally mounted in the work chamber, a pumping piston reciprocally mounted in the pressure-generating chamber, a collar loosely fitting around the work piston, a lever fulcrumed on the pumping piston, a guide bore in the body axially with the pumping piston, said pumping piston having an axial portion slidable in said guide bore, and a rod operatively connecting one end of the lever to a peripheral portion of the collar.

11. In a jack the combination of a body presenting a pressure chamber, a pressure generating cylinder and a fluid reservoir; a ram reciprocably mounted in the chamber; valve controlled ports interconnecting the pressure chamber, the pressure generating cylinder and the reservoir; a pumping piston reciprocable within said pressure generating cylinder to force fluid into said chamber to elevate said ram; mechanical means for elevating said ram, including a reciprocable collar surrounding said ram and tiltable thereon into and out of locking engagement with said ram; and actuating means connected to said collar and to said pumping piston and movable to and fro to elevate said ram at first through said

5 mechanical means and subsequently through said pumping piston, said means including a yield in the connection to said collar for limiting the actuating force that may be applied to said collar by said actuating means.

12. In a jack the combination of a body presenting a pressure chamber, a pressure generating cylinder and a fluid reservoir; a ram reciprocably mounted in the chamber; valve controlled 10 ports interconnecting the pressure chamber, the pressure generating cylinder and the reservoir; a pumping piston reciprocable within said pressure generating cylinder to force fluid into said chamber to elevate said ram; mechanical means 15 for elevating said ram, including a reciprocable collar surrounding said ram and tiltable thereon into and out of locking engagement with said ram; actuating means operatively connected to said collar and to said pumping piston and having 20 a to and fro motion for step by step actuation of said mechanical means and for reciprocation of said pumping piston; and means interposing yield in the operation of said mechanical means effective to limit the actuating force that may be 25 applied to said ram through said mechanical means.

13. In a jack the combination of a body presenting a pressure chamber, a pressure generating cylinder and a fluid reservoir; a ram reciprocably mounted in the chamber; valve controlled 20 ports interconnecting the pressure chamber, the pressure generating cylinder and the reservoir; a pumping piston reciprocably mounted in the pressure generating cylinder for hydraulically 25 raising the ram; a collar loosely surrounding the ram; an actuating rod connected at one end to the peripheral portion of the collar; and an operating lever pivotally connected at longitudinally spaced points to the pumping piston and to the other end of the rod; and means providing 30 a yielding force inhibiting downward motion of said pumping piston in said pressure generating cylinder whereby said operating lever fulcrums on the piston to elevate said ram through said rod and said collar and whereby upon the contacting 35 of the work by said ram and the consequent imposition of a greater resistant load upon said ram, said means may yield to permit said lever to fulcrum upon said rod for actuation of said 50 pumping piston.
